G. E. BARKER

PIPE BENDING APPARATUS

Filed March 12, 1924

Patented June 16, 1925.

1,542,355

UNITED STATES PATENT OFFICE.

GUY EUGENE BARKER, OF WATERLOO, IOWA.

PIPE-BENDING APPARATUS.

Application filed March 12, 1924. Serial No. 698,797.

To all whom it may concern:

Be it known that I, GUY E. BARKER, a citizen of the United States, residing at Waterloo, in the county of Blackhawk, State 5 of Iowa, have invented certain new and useful Improvements in Pipe-Bending Apparatus, of which the following is a specification.

My present invention relates generally to 10 pipe bending apparatus, more particularly to a simple, inexpensive and readily portable apparatus of this character, my object being the provision of a hand device by means of which pipe may be bent easily and 15 quickly at various angles without flattening or pinching the pipe, and a further object is the provision of a device of this character capable of ready adjustment for different angles and having means whereby pipe may 20 be quickly engaged and just as readily released.

In the accompanying drawing which illustrates my present invention and forming a part of this specification:

25 Figure 1 is a perspective view of the complete device, illustrating its practical application,

Fig. 2 is a top plan view illustrating the 30 position of the parts upon initial engagement with the pipe to be bent,

Fig. 3 is a top plan view illustrating the 35 position of the parts at the completion of a right angle bend,

Fig. 4 is a vertical section through a portion 40 of the device taken substantially on the line 4-4 of Fig. 2,

Fig. 5 is a detail perspective view of the pipe gripping and bending segment,

Fig. 6 is a detail vertical section through 45 the adjustable stop, taken on the line 6-6 of Fig. 2, and

Fig. 7 is a detail vertical section through the adjustable roller pipe guide or abutment, taken substantially on the line 7-7 of

45 Fig. 2.

Referring now to these figures, my improved apparatus includes a base 10 which may in practice be suitably attached to a work bench or other support upon which 50 there is horizontally mounted a pair of intermeshing gear members 11 and 12, the latter disposed approximately at the center of the base 10 for rotation around an upright post or journal 13 and being of suitably 55 greater proportions than the gear 11, the latter of which is mounted upon an upright

post or journal 14 and has a polygonal upper extension 15 for the reception of a conformably shaped wrench 16 which with its handle 17 constitutes the means whereby the gear 11 may be manually rotated and rotative movement in this way conveyed or imparted to the larger or main gear 12.

A pipe-engaging and bending segment 18 whose inner curvature at least conforms to the periphery of the main gear 12, is provided upon its inner or concaved face with teeth 19 and 20 located adjacent to opposite ends thereof, to interfit the teeth of the main gear 12. The outer surface or convex face 65 of the segment 18 presents a small longitudinal groove 21 for the reception of a pipe 22 to be bent, as in Figs. 1 and 3, the segment, having intermediate its ends an angularly offset and vertically flanged pipe-gripping 70 extension 23, between the inner surface of the flange of which and the convex face of the segment just sufficient room exists for the reception of the pipe 22 with the segment in the position shown in Fig. 2 where 75 its said pipe-gripping extension projects therefrom at right angles to the plane in which the pipe is initially inserted for the bending operation.

At one side of the base 10 and at the opposite side of the main gear 12 with respect to the actuating gear 11, a clamping bolt 24 rises from the said base through the longitudinally slotted holder 25 of a guide roller 26 which in the bending operation forms 80 an abutment for the pipe to be bent, this guide roller 26 being mounted vertically upon a post 27 rising from the holder 25.

At the other side of the main gear 12 and adjacent to the actuating gear 11 a stop 85 member 28, which is lengthwise slotted, as at 29, is adjustably held in place by a screw 30 which threads in connection with the base 10 as seen particularly in Figs. 2, 3 and 6, this stop member being engageable by the forward end of the segment 18 with respect to the direction of its operative movement, so as to adjustably limit the extent to which 90 the pipe is bent.

The parts as set in Figs. 1 and 2 are for 95 a right angle bend of the pipe 22 and after the segment 18 is set in the position of Fig. 2 with its pipe-gripping extension 23 adjacent to the guide roller 26, it is free to receive the pipe 22 between its outer face at one end of its groove 21 and its vertically flanged gripping extension 23, the pipe be- 100 105 110

ing disposed against the inner face of the guide roller 26. By then rotating the actuating gear 11 clockwise by means of the wrench 16 and handle 17, counter-clockwise movement is imparted to the main gear 12, and as this movement progresses the pipe will be gripped by the extension 23 and the bending operation will start, as in Fig. 1, the pipe being carried lengthwise with the bending segment. During this movement, the roller 26 forms an abutment to prevent the pipe from swinging off of the base 10 although at the same time it permits the pipe to readily move lengthwise. As the bending operation continues, the pipe will be bent to the desired point and if a right angle bend is desired the stop 28 is set as in Fig. 3 so that when engaged by the forward end of the segment 18, as shown in this figure, a true right angular bend will be formed in the pipe 22. It is then only necessary to rotate the parts in a reverse direction until the original position of Fig. 2 has been reached when the properly bent pipe may be easily lifted out of the machine, it being obvious that in this latter movement for the purpose of freeing the pipe, the pipe is at liberty to swing inwardly away from the guide roller or abutment 26. It is, furthermore, obvious that by adjusting the guide roller or abutment 26, as well as the stop member 28, the degree of curvature or bend of the pipe may be readily controlled, and it is likewise obvious that in its bending, pinching or flattening of the pipe will be avoided owing to the uniform even engagement of the bending segment with the work, and the gradual flexure of the work during the bending operation.

My invention thus provides a machine of the type specified which is simple, strong and durable, which permits of effective operation and uniform results, and which is not only inexpensive in the first instance, but with ordinary care will operate thereafter without expense.

It is also obvious that in view of the manner of engaging and supporting the segment in connection with the main gear, segments of

different shapes and sizes may be employed, depending upon the size and character of the pipe to be bent as well as the particular shape of the bend desired, and that a variety of such segments are adapted for ready interchangeable association with the main gear 55 in the manner specified.

I claim:

1. A device for manually bending pipe consisting of a main gear and an actuating gear in intermeshing relation, the latter having means providing for its manual rotation, a pipe bending segment associated with and conforming to the peripheral curvature of the main gear and having teeth upon its inner face engageable with the teeth of said gear at spaced points of the latter, a pipe-gripping member carried by said segment, and a pipe guide adjacent to the main gear forming an abutment for the pipe during the bending operation. 70

2. A pipe-bending machine consisting of a support, a gear mounted to rotate flatwise on the support, an actuator for said gear, an externally grooved and internally toothed bending segment detachably in association with said gear having a pipe-gripping element, a pipe-engaging abutment mounted on said support adjacent to one side of the gear, and a stop member on the support approximately diametrically opposite to said abutment for engagement by the forward end of the segment in its rotation with the gear. 75

3. A pipe-bending machine consisting of a support, a gear mounted to rotate flatwise on the support, an actuator for said gear, an externally grooved and internally toothed bending segment detachably in association with said gear having a pipe-gripping element, a pipe-engaging abutment mounted on said support adjacent to one side of the gear, a stop member on the support approximately diametrically opposite to said abutment for engagement by the forward end of the segment in its rotation with the gear, the said abutment and said stop member 95 being adjustable on the support, for the purpose described.

GUY EUGENE BARKER.
